(57) **CLAIM**

We claim the ornamental design for a vehicle roof, as shown and described.

DESCRIPTION

FIG. 1 is a top perspective view of a vehicle roof, showing a first embodiment of our new design;

FIG. 2 is a bottom perspective view of FIG. 1;

FIG. 3 is a top plan view of FIG. 1;

FIG. 4 is a bottom plan view of FIG. 1;

FIG. 5 is a front elevational view of FIG. 1, the rear elevational view being a mirror image thereof;

FIG. 6 is a left-side elevational view of FIG. 1, the right-side elevational view being a mirror image thereof;

FIG. 7 is a top perspective view of a second embodiment thereof;

FIG. 8 is a bottom perspective view of FIG. 7;

FIG. 9 is a top plan view of FIG. 7;

FIG. 10 is a bottom plan view of FIG. 7;

FIG. 11 is a front elevational view of FIG. 7, the rear elevational view being a mirror image thereof; and,

FIG. 12 is a left-side elevational view of FIG. 7, the right-side elevational view being a mirror image thereof.

The broken lines showing a vehicle and corner portions of the windows in the figures depict environmental matter and form no part of the claimed design. The remaining dot-dash broken lines represent a boundary of the claimed design.
